DESIGN.

H. F. QUINT & J. H. MOWEN.

ORNAMENTATION OF BURIAL CASKETS.

No. 16,418.

Patented Dec. 15, 1885.

UNITED STATES PATENT OFFICE.

HENRY F. QUINT AND JOHN H. MOWEN, OF BROOKLYN, NEW YORK.

DESIGN FOR ORNAMENTATION OF BURIAL-CASKETS.

SPECIFICATION forming part of Design No. 16,418, dated December 15, 1885.

Application filed October 1, 1885. Serial No. 178,778. Term of patent 7 years.

To all whom it may concern:

Be it known that we, HENRY F. QUINT and JOHN H. MOWEN, citizens of the United States, residing in the city of Brooklyn, in the county 5 of Kings and State of New York, have invented a new and useful Design for the Ornamentation of Burial-Caskets; and we do declare the following to be a full, clear, and exact description of the invention, such as will enable 10 others skilled in the art to which it appertains to make and use the same, reference being had to the accompanying photograph, and to the letters and figures of reference marked thereon, which form a part of this specification.

15 The design is for the ornamentation of coffins; and it consists in a surface for the same provided with a series of alternate puffs and depressions and alternate combs and depressions, and of inclines upon the combs and 20 puffs.

The figure shown is in perspective, referring to which, A designates the molding, B the top panels, and C the side panels. These panels are formed into alternate combs c , puffs c' , and 25 depressions c'' , each puff and comb having inclines c^3 . The puffs and combs are arranged

in such series as to present horizontal lines and distinct lines midway between said horizontal line and an imaginary line drawn at right angles thereto, or in angles of forty-five 30 degrees thereto.

The alternate combs, puffs, and depressions, together with the inclines of the puffs, give a diversity of lights and shades from any point of view, and constitute a rich heavy orna- 35

mentation.

What we claim as new is—

The design for coffin ornamentation, which consists in the panels having alternate combs c and depressions c'' and alternate puffs c' and 40 depressions c^3 , the puffs and combs having inclines c^3 , and arranged to present regular lines at right angles and angles of forty-five degrees from a true line, as illustrated and set forth.

In testimony whereof we affix our signatures 45 in presence of two witnesses.

HENRY F. QUINT.
JOHN H. MOWEN.
